UNITED STATES PATENT OFFICE.

EDWARD W. DAVIS, OF MINNEAPOLIS, MINNESOTA.

MAGNETIC CONCENTRATOR.

Application filed January 14, 1921. Serial No. 437,280.

To all whom it may concern:

Be it known that I, EDWARD W. DAVIS, a citizen of the United States, resident of Minneapolis, county of Hennepin, State of Minnesota, have invented certain new and useful Improvements in Magnetic Concentrators, of which the following is a specification.

This invention relates to improvements in magnetic concentrators. Such apparatus is particularly adapted for use in making magnetic iron assays in connection with iron ore. It is old in this art to employ a glass tube connected to a source of water and to hold the tube adjacent the poles of an energized electromagnet and thereafter to drop the sample of the iron ore to be tested in the upper end of the tube whereupon, during descent, the non-magnetic particles of the sample pass through the field and descend to the lower end of the tube, the magnetic portions being attracted and retained by the magnetic field. It is old, too, to permit water to pass through the tube to wash the magnetically attracted particles to remove any adherent non-magnetic material. During the passage of water through the tube, it is customary gently to reciprocate the tube lengthwise in the magnetic field and, coincidentally, to oscillate the tube substantially on its longitudinal axis. The novelty in this improved apparatus principally resides in the mechanical means provided automatically to effect such reciprocatory and oscillatory movements.

The object of this invention, therefore, is to provide an improved magnetic concentrating apparatus.

Other objects of the invention will more fully appear from the following description and accompanying drawings and will be pointed out in the annexed claims.

In the accompanying drawings, there has been disclosed a structure designed to carry out the objects of the invention, but it is to be understood that the invention is not confined to the exact features shown, as various changes may be made within the scope of the claims which follow.

50 In the drawings:

Figure 1 is a front elevation of the apparatus, a portion thereof being diagrammatic;

55 Figure 2 is an enlarged detailed view in front elevation of the mechanism for hold-

ing and moving the test tube, the core being broken away;

Figure 3 is a section on the line 3-3 of Figure 2;

Figure 4 is a section on the line 4-4 of 60 Figure 2; and

Figure 5 is a detailed view in plan of the slide and associated parts.

The selected embodiment here disclosed of this invention is one particularly adapted 65 for laboratory use in testing the magnetic iron content of a sample of iron ore. The apparatus consists of an elevated water tank 6 having a water inlet 7 connected to a suitable source of supply, and an overflow outlet 8. A pipe 9 communicates with the interior of the tank 6 and is adapted to draw water therefrom. A pipe 11, carried by and communicating with the pipe 9, is provided with an intermediate valve 12 to control 70 the gravity flow of water therethrough. The pipe 11 is terminally connected to a flexible water supply tubing 13 which, at its other end, is fitted over the annular shoulder 14 of the side-opening of the tube 15 which is preferably of glass in order to permit view of the operation. The upper end of the tube is open and terminally flared and is adapted to be closed by means of the rubber stopper 16. The open lower end of the tube is fitted with a short piece of rubber tubing 17 upon which is clamped a suitable stop-cock 18. A flexible rubber tubing 19 is fitted to the lower open end of the pipe 9 and the lower end of this tubing is fitted with a 80 valved outlet member 20.

The tube is adapted to be movably carried by a sleeve suitably mounted and actuatable to cause the substantially middle portion of the tube to be moved adjacent the 95 poles 22 of an electromagnet. This electromagnet preferably consists of an iron core 23 bent to provide the opposed poles 22, and provided with the usual winding 24 through which electric current may be passed upon closure of the usual circuit through the switch 25. The core 23 is supported by any suitable standards 10, as diagrammatically illustrated in Figure 1, which rest upon a base indicated by the surface line 27. 100

As stated, this invention particularly relates to the mechanical means for imparting a turning or oscillatory and a reciprocatory motion to the tube. The word turning or oscillation and forms thereof 110

are here employed to describe the partial turning of the tube, back and forth, upon its longitudinal axis; while the word reciprocation and its forms are employed to describe the up and down movement of the tube substantially in the direction of its longitudinal axis.

A frame, having suitably braced metallic side rails 26, is preferably provided with 10 integral rings 46 within which are received the core portions adjacent its poles 22. The frame is thereby held by the core so that the middle portion of the tube is slidable upon the rounded pointed poles 22 of the 15 electromagnet as indicated in Figures 2 and 3. A metallic plate 28, arcuately curved in cross-section, is fixedly secured in position between the side rails by means of the legs 29 screwed to the rails. The concave face 20 of this plate is outwardly presented while its sides are relatively built up to form integral stationary guides 31. The carriage, adapted to be slidably reciprocated upon these guides, comprises side-blocks 32 suitably grooved to receive the stationary guides 31 in slidable engagement. A plate 33 is 25 secured at its sides to the two upper faces of the blocks 32 by means of the screws 34. This plate 33 is curved similarly to the plate 28 and is carried by the blocks 32 in running engagement with the concave face of the former. A slot 35 is transversely cut in the curved portion of the plate 33 and is adapted partially to register with a 30 slot 36 in the fixed plate 28. The slot of the fixed plate is cut diagonally to the direction of reciprocation of the carriage as is clearly shown in Figure 5.

The holder for the container comprises a 40 cylindrical sleeve 37 whose external surface effects a smooth running fit with the inner surface of the arcuately curved carriage plate 33. This sleeve 37 is provided with a pin 38 which is preferably integral therewith. This pin is adapted to be inserted within and to project through, the space defined by the registry of the superposed slots. The pin 38 carries rollers freely revoluble thereon. The lower roller 39 is adapted to 45 engage the sides of the slot 36 in the fixed plate 28 while the upper roller 41 similarly engages the sides of the slot 35 of the slideable plate 33. Therefore, when the carriage is reciprocated, the sleeve carried thereby 50 is not only reciprocated but is also simultaneously oscillated due to the cam action of the roller-bearing pin 38 in following the diagonal slot 36 in the fixed plate 28 while coincidentally following the slot 36 in the 55 slideable plate 33.

The holder is made in such form in order to receive the glass tube 15. A rubber collar 42 is preferably placed around the upper portion of the tube 15. This collar, when 60 positioned on the tube, is adapted to be re-

ceived within the sleeve 37 so that the tube is frictionally and resiliently held by the sleeve. The lower portion of the tube 15 is slidably supported in a saddle 43 adjustably mounted in a slot in the cross-bar 44 of the side-rail frame. The saddle 43 is held in adjusted position by means of the thumb-screw 45.

A simple mode of reciprocating the carriage is afforded by the small electric motor 47 and its associated mechanism. The motor is substantially of a spheroidal external conformation and is provided with a tightly fitting metallic strap 48 having opposed trunnions 49 pivotally mounted in brackets 51 secured by bolts 52 to one of the rails 26. The motor is held in the desired axially angular position with relation to the rails by means of adjusting screws 40 received in threaded engagement in the brackets and 55 engaging the trunnions. The shaft 53 is coupled directly to the motor shaft and is revolvably supported by the bearings 54 carried by the arms 55 and 56 projecting from one rail 26. The upper end of the shaft 53 is provided 60 with a worm 57 meshing with a worm wheel 58 fast on a crank-shaft 59 revolvably borne by the bearings 60 on the side rails 26. The crank arms through the pin 50 carry the bearing block 62 secured to the upper end 65 of the connecting rod 63 which is pivotally carried at its lower end by the pin 64 (see Figure 4) mounted in ears 65 oppositely depending from the curved bar 66 secured by the screws 67 to the slideable blocks 32 of 70 the carriage. The electric motor 47 is adapted to be driven from a suitable source of current not necessary to be shown through the switch 21. Preferably a tension spring 75 69 is secured at one end to the side rail 26 and at its other end to the ear 70 of one block 32 of the carriage. This spring is 80 preferably employed to counteract the weight of the reciprocating parts as the frame is held in an inclined or upright position.

The preferred manner of operation of the apparatus here disclosed is as follows: The stop-cock 18 is closed and the valve 12 is 85 opened sufficiently to fill the tube nearly to its top. The switch 25 is closed and the electromagnet energized. A ten gram sample of the ore to be assayed, which has 90 previously been pulverized to pass a screen of one hundred meshes to the square inch, is poured into the upper end of the tube and settles down through the water until it reaches the poles of the electromagnet where a part of it stops in the magnetic field. After washing out the cap or flared 95 upper end of the tube, the stopper 16 is tightly positioned in the tube end. The valve 12 is then opened, as is also the stop-cock 18 of the outlet tubing 19. After opening 100 the latter, water flows, via the supply 105

tubing 13, into the upper end of the tube and runs out the lower end thereof, carrying with it all freed non-magnetic material. Such non-magnetic material and water are preferably collected in the evaporating pan 68 conveniently supported upon a base below the level of the lower end of the tube. The motor 47 is then started whereby a relatively slow reciprocating movement up and down of the carriage and tube is effected while coincidently an oscillatory movement is imparted to the tube. The purpose of these two movements is to free the non-magnetic portion of the ore and to allow the down-flowing current of water to carry such portion into the evaporating pan. Such movements are continued until no more non-magnetic material can be washed out of the tube. The portion remaining under attraction in the field of the electro-magnet is clean magnetic concentrate and this is removed from the tube and placed in a suitable receptacle. The removal is preferably effected by stopping the motor 25 and by demounting the tube from its holder and slowly raising it until the magnetic material held in the field is near the bottom of the tube. The water supply is then cut off at the valve 12 and the rubber stopper 16 is removed from the mouth of the tube. The speed of water outlet from the tube is governed by the stop-cock 18 so that, as the level of the water in the tube reaches the level of the concentrate, the stop-cock 35 18 is closed and the tube is removed from between the poles of the magnet and all the tube contents are removed from the tube into a suitable cup which may thereafter be held in the magnetic field whereby the 40 concentrate will be retained in the cup while the water is decanted therefrom.

I claim as my invention:

1. In a magnetic concentrator, the combination of a frame, an elongated container for the material to be concentrated mounted in substantially upright position to reciprocate on said frame, magnetic means positioned adjacent an intermediate portion of the container to create a magnetic field only at intermediate portions of the container, and means to reciprocate the container substantially along its upright axis in said field whereby magnetic particles of the material will be retained by the field in the intermediate portions of the container and non-magnetic particles thereof will drop therethrough.

2. In a magnetic concentrator, the combination of a frame, a container for the material to be concentrated mounted to have oscillatory turning movement on the frame, a magnet positioned to create a magnetic field adjacent the frame, and means oscillatorily to turn the container in said field whereby to facilitate the retention of mag-

netic particles of the material in the field and to facilitate the drop of the non-magnetic particles thereof through the field.

3. In a magnetic concentrator, the combination of a frame, a container for the material to be concentrated mounted on said frame in upright position to reciprocate substantially along its upright axis and to have an oscillatory turning movement about said axis, a magnet positioned to create a magnetic field adjacent the frame, and means to reciprocate and to oscillate the container in said field whereby magnetic particles of the material will be retained in the field and the non-magnetic particles thereof will drop therethrough.

4. In a magnetic concentrator, the combination of a frame, slideways fixedly mounted in spaced relation on the frame, a carriage slidably mounted on the slideways and adapted to reciprocate thereon, a container for the material to be concentrated mounted to oscillate on the carriage, a magnet positioned to create a magnetic field adjacent the frame, and means operable simultaneously to reciprocate the carriage and to oscillate the container in said field whereby magnetic particles of the material will be retained in the field and non-magnetic particles thereof will drop therethrough.

5. In a magnetic concentrator, the combination of a frame, a carriage mounted to reciprocate on said frame, a container for the material to be concentrated mounted to oscillate on said carriage, a magnet positioned to create a magnetic field adjacent the frame, and means operable simultaneously to reciprocate said carriage and to oscillate said container in said field whereby magnetic particles of the material will be retained in the field and non-magnetic particles thereof will drop therethrough.

6. In a magnetic concentrator, the combination of a frame, a plate secured to the frame, a carriage mounted to reciprocate on said plate, the plate having a slot extending diagonally to the axis of reciprocation of the carriage, and the carriage having a slot extending transversely to said axis, a container for the material to be concentrated, a holder therefor, the holder having a pin adapted to project through both slots whereby, upon reciprocation of the carriage, the holder is caused to oscillate, a magnet positioned to create a magnetic field adjacent the frame, and means to reciprocate the carriage in said field whereby magnetic particles of the material will be retained in the field and non-magnetic particles thereof will drop therethrough.

7. In a magnetic concentrator, the combination of a frame, an arcuately curved plate affixed to the frame, a similarly curved plate reciprocally movable on the fixed plate, the fixed plate having a slot extend-

ing diagonally to the axis of reciprocation of the movable plate and the latter having a slot extending transversely to said axis, a container for the material to be concentrated, a sleeve to hold the container and shaped to be positioned on said movable plate, a pin on the sleeve to project through both slots whereby, upon reciprocation of the movable plate, the sleeve is caused to oscillate thereon, a magnet positioned to create a magnetic field adjacent the frame, and means to reciprocate the movable plate in said field whereby magnetic particles of the material will be retained in the field and non-magnetic particles thereof will drop therethrough.

8. In a magnetic concentrator, the combination of a frame, a container mounted in upright position to reciprocate on said frame and adapted to permit the material to be concentrated to drop therethrough, means to produce a magnetic field adjacent

the container whereby the drop of magnetic particles of the material is arrested, and means to reciprocate the container substantially along its upright axis in said field whereby the magnetic separation of the particles of the material is facilitated.

9. In a magnetic concentrator, the combination of a frame, a container for the material to be concentrated, a substantially cylindrical holder for the container, a carriage mounted to reciprocate on the frame and having an arcuate bearing portion for said holder, means to create a magnetic field adjacent said container, and means operable to reciprocate the carriage and to oscillate the holder on said bearing surface whereby magnetic particles of material will be retained in the field and non-magnetic particles thereof will drop therethrough.

In witness whereof, I have hereunto set my hand this 7th day of January 1921.

EDWARD W. DAVIS.
